Primary Examiner — Thomas Johannes*Assistant Examiner* — Khawaja Anwar(74) Attorney, Agent, or Firm — Greenberg Traurig, LLP(57) CLAIM

The ornamental design for a loom, as shown and described.

DESCRIPTION

FIG. 1 is a top perspective view of a loom showing my new design;

FIG. 2 is a front elevation view thereof;

FIG. 3 is a rear elevation view thereof;

FIG. 4 is a right side elevation view thereof;

FIG. 5 is left side elevation view thereof.

FIG. 6 is a top plan view thereof; and,

FIG. 7 is a bottom plan view thereof.

The broken line in the drawings shows unclaimed subject matter only and forms no part of the claimed design.

1 Claim, 3 Drawing Sheets(56)
